UNITED STATES PATENT OFFICE.

CHARLES F. CATTELL, OF WEST CHESTER, PENNSYLVANIA.

APPARATUS FOR FEEDING FUEL TO GAS-GENERATORS.

No. 877,905.

Specification of Letters Patent.

Patented Feb. 4, 1908.

Application filed June 25, 1908. Serial No. 323,254.

To all whom it may concern:

Be it known that CHARLES F. CATTELL, citizen of the United States, residing at West Chester, in the county of Chester and State of Pennsylvania, has invented certain new and useful improvements in Apparatus for Feeding Ground Fuel to Gas-Generators, of which the following is a specification.

My invention relates to apparatus for feeding ground fuel to gas generators and has for its main object to improve the construction of such apparatus in various particulars, whereby, a uniform and superior quality of gas will be quickly generated, and the clogging of the generator and adjuncts, from carbon and like products, will be materially lessened; and with this and minor objects my invention consists of the parts and combination of parts as will be hereinafter more fully pointed out.

In the drawings: Figure 1 is a front elevation of my ground fuel feeding apparatus for gas generators, parts being broken away and parts in section. Fig. 2 is a side elevation 25 of the same. Fig. 3 is a top plan view, parts being in section. Fig. 4 is a detail view.

1 represents the generator on which is secured the generator lid plate 2 with which it has a planed and finished gas-tight joint. 36 This lid plate is secured on the generator in position by the pressure exerted by the two screws 3, the shoulders of which bear on the forked ends 4 of the cotter bar 5; said bar transmits the pressure to the lid at the center, by reason of its central annular opening 6 fitting over the boss 7 which is integral with the lid 2.

8 is a water cooled casting in the generator which is bolted to the under faces of the lid 40 2 whereby the lid is also kept cool, said casting having a central cylindrical opening or space 9, the lower end of which is flared as at 10. A branch opening leads into said space through which fuel is fed to the rotating 45 vanes.

11 and 12 are standards bolted to the lid 2 on which are bolted standards 13, 14, 15 and 16 which form a frame and are suitably mounted to form slides secured together by 50 bolts 17 and 18 at the top and provided with a ring 19 by means of which the whole machine is raised.

An overflow box 20 which receives the water that has been used to cool the shaft 21, 55 slides between the standards 14 and 15 as

clearly shown in Fig. 1, said box or tank having an annular opening in its bottom from which a tubular extension 22 extends upwardly into the tank to a point below the top of the tank; said shaft being rotated within the tubular extension 22, as will be herein-after described.

23 is an annular rim on the end of the shaft overlapping the joint between the shaft and tube 22. The top 24 of the overflow tank 65 is provided with an annular perforated lug 25 which supports the tube 38 which conveys the cooling water to the base of the shaft 21.

The shaft 21 has a bearing in the lug 7 of the lid 2 and extends into the generator 70 through the space 9 in the water casting 8. The lower end of the tubular shaft 21 is enlarged to form the truncated cone 26 which is also hollow and of slightly smaller (when hot) diameter than the diameter of the space 75 9 in the casting 8.

27 and 28 are two winged vanes secured to the shaft 21 which are adapted to be rotated at a high rate of speed and serve to feed and distribute the fuel evenly over the fuel bed. 80 The vanes are within the space 9 and are protected from the direct heat of the burning fuel by means of the water cooled casting 8.

29 is a bearing block on which the standards ⁸⁵ a and b are bolted, said standards supporting the bottom of the overflow-box 20 to which they are bolted, said block being provided with projections 30 which are slidably mounted in the slots 39 formed by the standards 13 and 14 and 15 and 16. This block is 90 provided with a central opening through which the shaft 21 passes; 31 is a recess formed in the block, around said shaft opening, in which a projection 32 fixed to the shaft is positioned. Bearing block 29 is provided 95 with follower nuts 33 and 34 which project into the recess 31 and are adapted to bear on the projection or shoulder 32 of the shaft 21.

35 is a hand lever fulcrumed at 36 on one side of the standard 13 while its extreme 100 lower end is pivotally secured at 37 to one of the projections 30 of the bearing block whereby said block may be raised and lowered, thus raising the shaft 21 and the overflow box 20 and preserving the relative positions 105 of these parts.

A small vertical water tube 38 is secured within the tubular shaft 21, its lower end terminating in the truncated cone 26 while its upper end extends beyond the upper end of 110

the shaft into the perforated lug 25 on the cover of the tank 20. Water from this tube is introduced into the truncated cone, passes up the shaft 21 and is discharged into the overflow tank 20.

40 is a frame bolted between the standards 11 and 12 (see Fig. 1) having a central bearing 40* in which the spur wheel 41 is journaled thus allowing shaft 21 to be raised and lowered without displacing the spurwheel 41, said wheel being connected to the shaft 21 by means of the long feather keys 42 which are fixed to the shaft 21.

43 is a power shaft journaled at its upper 15 end in a bearing 44 while its lower end is journaled in a step bearing 45 on the lid 2.

46 is a gear wheel keyed to the shaft 43 and meshing with the spur wheel 41. The shaft 43 is geared to revolve at about 750 revolutions per minute giving the shaft 21 a speed of about 1,800 revolutions per minute, through the train of gears 41 and 46.

The ground fuel which is fed into the machine by a flexible pipe attached to a hopper 25 (not shown) through the pipe 47, the supply of which is regulated by means of the valve 48, passes as it falls through the neck 59 onto the screw 50. The screw 50 is rotated by means of the gears 51 and 52 through the shaft 53 in the bearing 54 to the set of gears 55 which takes power from the shaft 43 by bevel gears 56, 57 and 58, the gear 58 being keyed to the shaft 43. The teeth of gear 51 are cut at 45°. The coal-supply chute has a 35 vertical leg 59 and a leg 60 disposed at an angle thereto and leading towards the vanes 27 and 28 onto which the fuel is delivered. The screw 50 is journaled in the leg 59 and has a step bearing in the leg 60 which is cast 40 integral with the lid 2.

The operation of the apparatus is as follows: Ground fuel (preferably bituminous coal) is placed in a hopper (not shown) above the apparatus. The generator is started up 45 in the usual way until a good fuel bed is accumulated (preferably of anthracite coal, or oven coke) (using the usual air blast to build up said fuel bed), then the air blast is shut off and steam introduced under the grate bars 50 and the stack valve closed, then the ground fuel is fed to the apparatus and distributed over the fuel bed by the rotating vanes 27 and 28 attached to shaft 21. The proper proportion of ground fuel is fed into the generator at each "run" to produce from 1 to 2% of residue coke on top of said fuel bed. The duration of a "run" (in making water gas) is usually 6 to 7 minutes. After the "run" is made, the ground fuel is shut off 55 from the generator and the shaft 21 raised by means of the hand lever 35 and block 29 until the vanes are well within the space 9 whereby they are protected from the heat, by reason of the truncated cone 26. Then the 60 steam is shut off from under the generator

grate bars, whereupon the stack valve (not shown) is opened. The air blast is then turned on to again bring the fuel bed to a proper heat, which usually takes from six to seven minutes when we can then: 1st, turn 70 off the air blast; 2nd, turn on the steam under the grate bars; 3rd, close the stack valve; and 4th, start the feeding apparatus and feed in the ground fuel. As the ground bituminous coal is sprinkled by the vanes 27 75 and 28 over the hot fuel bed, the gas is instantly extracted from the small particles of fuel, some of it even before it reaches the fuel bed as the heat is from 2800° to 3200° Fahrenheit in the chamber above the said fuel bed. 80

With the feeding apparatus, I first, instantly extract the gas from the coal about 5 cubic feet, per pound of bituminous coal; second, retain the coke on the fuel bed (which automatically keeps up said fuel bed) 85 third, when making a "run", I make "water" gas from the coke which is a residue from the ground bituminous coal. The two gases (coal and water) are mixed in the generator. It requires but one-half of the oil to enrich 90 the ground fuel gas to the required candle power. Fifth, the ground fuel gas will make an excellent heating gas of about 12 candle power without any oil as enricher. A low grade of bituminous coal can be used successfully with my improved ground feed mechanism. The ground fuel may also be fed or sprayed into the generator with compressed gas or air, or steam. The vanes 27 and 28 serve as "trimmers" for the ground 100 fuel. That is to say, they whirl the fuel over the fuel bed. The fuel bed is loosened up (when necessary) by a clinker bar from the top of the generator.

What I claim is:

1. The combination with a gas generator, of a shaft, a truncated cone on the lower end of the shaft, agitators above said cone, and a fuel chute leading to said agitators.
2. In combination with a gas generator, a 110 shaft, a truncated cone on the lower end of said shaft, and fuel distributing vanes secured to said shaft.
3. The combination with a gas generator, of a shaft, a truncated cone on the lower end 115 of the shaft, fuel distributing vanes on said shaft and means for raising and lowering said shaft.
4. The combination with a gas generator, of a hollow shaft, a truncated cone on the lower 120 end of said shaft, fuel distributing vanes on said shaft, and a water tube within said shaft and discharging into said cone, said shaft having a discharge opening at its upper end.
5. The combination with a gas generator, 125 of a water jacket, of a shaft, vanes secured on said shaft, and means to raise said shaft to bring the vanes within the water jacket.
6. The combination with a gas generator, of a water jacket, a shaft, a truncated cone 130

on the lower end of said shaft, vanes secured to said shaft and means to raise the shaft to bring said vanes within the water jacket.

7. The combination with a gas generator, of a hollow shaft, a truncated cone on the lower end thereof, a water pipe secured in said shaft, and discharging into said cone, a discharge tank into which water is discharged from the upper end of said shaft.
10. 8. The combination with a gas generator, of a hollow shaft, a truncated cone secured on the lower end thereof, a water pipe secured in said shaft and discharging into said cone, a discharge tank into which water is discharged from the upper end of said shaft, of means to move said hollow shaft in connection with said tank.

9. The combination with a gas generator, of a lid for the same, a water jacket suspended from said lid, a shaft surrounded by

said jacket, vanes secured to said shaft and a truncated cone on the lower end of said shaft.

10. The combination with a gas generator, of a fuel feed comprising a shaft, vanes secured radially on said shaft and a truncated cone on said shaft at the lower ends of said vanes.

11. The combination with a gas generator, of a fuel feeding means, of a shaft carrying said vanes, a slideable bearing block, on said shaft, means preventing a relative sliding movement of the block and shaft, and means to move said block, shaft and feeding means simultaneously.

In testimony whereof I affix my signature in presence of two witnesses.

CHARLES F. CATTELL.
